Des. 236,358
Patented Aug. 19, 1975

236,358

CIGARETTE LIGHTER

William R. Forelli, 19 Compo Road,
Westport, Conn. 06880

Filed May 24, 1974, Ser. No. 472,976

Term of patent 14 years

Int. Cl. D27—05

U.S. Cl. D27—39

Fig. 1

Fig. 2

Fig. 3

Fig. 4

Fig. 5

Fig. 6

FIG. 1 is a perspective view of a cigarette lighter showing my new design;

FIG. 2 is a top view of the lighter of FIG. 1;

FIG. 3 is a left-side view of the lighter of FIG. 1;

FIG. 4 is a front view of the lighter of FIG. 1;

FIG. 5 is a right-side view of the lighter of FIG. 1; and

FIG. 6 is a bottom view of the lighter of FIG. 1.

I claim:

The ornamental design for a cigarette lighter, substantially as shown and described.
